(57) **CLAIM**

The ornamental design for a monitor stand, as shown and described.

DESCRIPTION

FIG. 1 is a perspective view of a monitor stand.

FIG. 2 is a front elevation view thereof.

FIG. 3 is a top plan view thereof.

FIG. 4 is a rear elevation view thereof.

FIG. 5 is a bottom plan view thereof.

FIG. 6 is a right side elevation view thereof.

FIG. 7 is a cross sectional view thereof taken along the line 7—7 in FIG. 2.

FIG. 8 is a cross sectional view thereof taken along the line 8—8 in FIG. 2.

FIG. 9 is a cross sectional view thereof taken along the line 9—9 in FIG. 8.

FIG. 10 is an enlarged view of the portion of the monitor stand shown in FIG. 8.

FIG. 11 is an enlarged view of the portion of the monitor stand shown in FIG. 9.

FIG. 12 is a referential perspective view thereof where the monitor suspension is taken down; and,

FIG. 13 is a referential perspective view thereof with the monitor.

The portion of the article shown in broken lines is for the purpose of showing environmental structure only and forms no part of the claimed design.
